GOLF CLUB

Ralph F. Wheeler, Springfield, and Emil J. Marciniak, Easthampton, Mass., assignors to A. G. Spalding & Bros. Inc., Chicopee, Mass., a corporation of Delaware

Application June 27, 1946, Serial No. 679,772

13 Claims. (Cl. 273—80)*

1

This invention relates to improvements in golf clubs, particularly in means for receiving and fastening the shaft of a golf club in a molded plastic head therefor.

It is an object of this invention to provide a metal connector in the form of a sleeve adapted to be secured to a shaft, of simple, light construction, convenient and economical to manufacture, and including means for firmly anchoring the sleeve in a molded object particularly the head of a golf club, in a socket or hosel thereof so as to resist torque and shearing force, the sleeve providing substantial reinforcement for the shank and body of the head of the club and providing a firm base for attachment of the head or other molded plastic article to a shaft extending into its hosel or socket.

Heretofore, it was customary to construct golf club heads of wood or metal, and to secure a shaft in the hosel or socket by various conventional fastening means for engaging the wood or metal of the head. More recently, it has been proposed to manufacture the head of a golf club, particularly for drivers, of molded plastic material.

Since the head and shank of the club are generally molded in one piece, it is desirable to incorporate means in the head in the molding operation for anchoring the shaft in the head, having interengagement with the plastic material capable of sustaining without failure the high torque and shearing force to which the connection is subjected when the club strikes a ball. Such anchoring means should reinforce rather than weaken the head and its connection with the shank. Moreover, when the anchoring means is made of metal, it should be of sufficiently light construction to avoid substantial effect upon the distribution of mass in the head. Construction of anchoring means fulfilling all of these prerequisites presents a relatively difficult problem.

In a preferred embodiment of my invention, I construct a sleeve or ferrule of metal having a plurality of fin-like projections thereon, formed by lancing out portions of the metal wall of the tube, extending outwardly and distributed around and along the sleeve, with an aperture at the base of each projection or fin. Moreover, additional apertures can be formed in the wall of the sleeve, similarly distributed along and around its surface, and preferably disposed diametrically opposite the apertures formed by outward lancing of said projections. The ferrule is advantage-

2

ously tapered so as to receive the shaft from its wider end and can be provided, if desired, with interior threads or other means for securing a shaft therein. The sleeve is molded in the head so as to lie co-axially with the hosel or socket in the shank of the head. The core piece for forming the hosel in the head extends into the sleeve to exclude plastic from that portion of the interior of the sleeve which is to receive the shaft. The plastic flows into and fills the apertures in the ferrule and surrounds and embeds the projections or fins extending from its surface. Moreover, the plastic flows into the space at the lower end of the sleeve beyond the end of the plug or core, providing an interlock with apertures along this portion of the sleeve. Interengagement of the projections and apertures of the ferrule with the plastic provides a firm anchorage therefor in the head of the club so that when the shaft is secured to the ferrule, a firm connection is formed between the shaft and the head.

The fins are lanced out so as to lie substantially in planes parallel to the axis of the sleeve, so that their surface portions engaging the surrounding plastic provide maximum resistance to torque tending to rotate the sleeve in the plastic. Moreover, in order to avoid any substantial camming action tending to force the plastic away from the sleeve when the connection is subjected to torque, the fins extend in a generally radial direction from the sleeve. Preferably, the fins extend from alternate sides of the apertures at their base, so that they offer similar resistance to torque in either direction.

An advantage of the preferred construction in accordance with my invention wherein apertures are formed diametrically opposite the lanced out projections lies in the fact that the latter can be conveniently formed by lancing out portions of the surface with a tool or instrument inserted through the oppositely disposed apertures.

Other objects and advantages of the invention will appear from the following description taken in connection with the accompanying drawing wherein:

Figure 1 is a perspective view of a ferrule or sleeve constructed in accordance with my invention.

Fig. 2 is a plan elevation of the sleeve of Fig. 1.

Fig. 3 is a side elevation, partly sectioned, of a golf club head assembled with a shaft, and including a sleeve in accordance with my invention.

Fig. 4 is a side elevation of a golf club head similar to Fig. 3, including a sleeve of modified construction.

Referring to the drawings, the ferrule in accordance with this invention comprises a tubular sleeve 10 of metal, tapering slightly so as to be slightly wider at its top than at its base, the taper being for example about 1:15. Along the upper part of the sleeve a plurality of projecting fins 11, advantageously shaped like a D, are formed by lancing out portions of the metal from the surface of the sleeve, leaving an aperture 11a in the wall of the sleeve at the base of each fin. The lanced out fins are distributed at spaced points longitudinally and circumferentially of the sleeve. For example, the lanced out fins can be formed at approximately 90° intervals around the sleeve, and arranged along a spiral or helix extending lengthwise thereof. The projections 11 preferably extend substantially in planes running lengthwise of the sleeve as shown in Fig. 2. As indicated in Fig. 2, the projections 11 are preferably lanced out on alternate sides of the resulting apertures. Preferably additional apertures 13 are formed in the sleeve 10 at points diametrically opposite to each of the apertures 11a formed by outward lancing of projections 11, apertures 11a and 13 being substantially uniformly spaced over the surface of the sleeve.

In manufacturing the illustrated form of the invention, apertures 13 are advantageously formed first and then projections 11 are lanced outward by insertion of the lancing tool through the corresponding opposite apertures 13.

Adjacent the base of the tube a plurality, for example, a pair of projections or fins 14, preferably of somewhat greater size than fins 11, are lanced outwardly on opposite sides of the sleeve 10 intermediate the ends of the tube. An internally threaded portion 15 can be provided intermediate the ends of the sleeve for engaging the threaded end 16 of a shaft 17, to which the sleeve is to be secured.

A head 18 for a golf club is molded of suitable plastic around the sleeve 10, the latter being disposed co-axially with the hosel or socket in the shank 18a which receives the shaft 17. The plastic material is excluded from the interior of the shaft-receiving portion of the sleeve 10, for example, by means of a conventional core or insert shaped like the end of the shaft 17, said insert or core being positioned in the sleeve 10 in the same manner as the shaft during the molding operation. The plastic material used to form the head 18 surrounds and embeds the outwardly lanced fins 11 and 14, and extends into the apertures 11a at the base of the fins, as well as apertures 13 in the upper portion of the sleeve, while at the lower end of the sleeve, the plastic material flows into the interior of the sleeve, extending through apertures 14a at the base of fins 14 forming an interlock therewith. Thus the sleeve 10 is firmly embedded in the body of the golf club head. Thereafter, if required, the lower end of the sleeve can be machined off so as to be flush with the lower surface of the head 18.

After removal of the core, the shaft 17 is inserted into the hosel and secured therein by engagement of threads 16 with corresponding internal threads 15 of the sleeve 10. However, other means can be used to secure the shaft in engagement with the sleeve. For example, as shown in Fig. 4, a sleeve 10a is provided which is similar to sleeve 10 except that the threads

15 on the sleeve are omitted. The end of the shaft 17a is secured in the sleeve 10a by means of cement, or by any other conventional fastening means such as rivets, screws or other wedging means (not shown) for wedging the shaft in the sleeve.

Projections 11 and 14 embedded in the plastic provide exterior engagement between the plastic and the sleeve while extension of the plastic into apertures 13 and 11a, and the interlock of the plastic extending through apertures 14a provide an interior engagement constituting a firm anchorage for the sleeve in the head, which resists withdrawal of the sleeve from the hosel, and especially resists torque applied when the golf club is used to strike a ball tending to rotate the sleeve in the head.

Distribution of fins 11 on alternate sides of apertures 11a equalizes resistance to torque acting between the sleeve 10 and the head 18 in opposite directions. To avoid substantial camming action tending to force the plastic away from the sleeve, fins 11 and 14 extend substantially in radial direction from the sleeve with their surface portions disposed longitudinally thereof. Thus, the fins are bent outward to form an angle of at least 60° with the tangent to the sleeve at the base, and preferably have their surfaces parallel to a radial plane of the sleeve which intersects the center of the aperture at the base of the fin or projection.

As indicated in the drawings, the sleeve in accordance with this invention can be readily secured to the end of a shaft so as to remain permanently secured thereto during use. While the sleeves 10 and 10a are shown as separate from the shaft 17, the sleeves can also be made integral therewith. A sleeve in accordance with this invention can be similarly used to provide a connection between a shaft and molded plastic articles other than golf club heads, wherever a firm anchorage and interconnection between the shaft or sleeve and the plastic material is required for resisting torque, shear and withdrawal from the plastic.

Variations and modifications may be made within the scope of this invention and portions of the improvements may be used without others.

We claim:

1. In a molded plastic article to be secured to a shaft to withstand high torque, means for connecting said shaft to said article comprising a metal sleeve secured to said shaft; a plurality of opposed laterally projecting fins lanced outward from the wall of the sleeve with an aperture in the wall at the base of each fin, said fins lying in longitudinal rows on the sleeve and extending in substantially radial direction therefrom, said fins being embedded in the plastic material of said article, and said plastic material extending into said apertures at least to the interior surface of the sleeve.

2. In a molded plastic article to be secured to a shaft to withstand high torque, means for connecting said shaft to said article comprising a metal sleeve secured to said shaft; a plurality of laterally projecting fins lanced outward from the wall of the sleeve with an aperture in the wall at the base of each fin, said fins lying in rows extending longitudinally of the sleeve and forming an angle of at least 60° with the tangent to the sleeve at the base of each fin; a plurality of apertures in said wall of the sleeve opposite said lanced out fins, said fins being embedded in the plastic material of said article,

and the plastic material extending into the apertures at the base of said fins and into the opposite apertures in the wall of said sleeve, at least to the interior surface of said sleeve.

3. In a molded plastic article having a socket for receiving the end of a shaft, means in said socket for connecting said shaft to said article comprising a metal sleeve for engaging the end of the shaft with the latter extending part way into the sleeve; a plurality of laterally projecting fins lanced outward from the wall of the sleeve with an aperture in the wall at the base of each fin, said fins being embedded in the plastic material and the plastic material extending into said apertures at the base of the fins along the shaft-receiving portion of the sleeve to the interior surface of the sleeve, and extending into the interior of the sleeve through the apertures at the bases of said fins beyond the shaft-receiving portion of the sleeve.

4. In a molded plastic article having a socket for receiving the end of a shaft, means in said socket for connecting said shaft to said article comprising a metal sleeve for engaging the end of the shaft with the latter extending part way into the sleeve; a plurality of laterally projecting D-shaped fins lanced outward from the walls of the sleeve with an aperture at the base of each fin, said fins being lanced out outward alternately on opposite sides of the aperture at their base, and being embedded in the plastic material of said article; and said plastic material extending into said apertures at least to the interior surface of the sleeve.

5. In a molded plastic head for a golf club having a shank and a hosel extending into the head through said shank; means in said hosel for securing said head to a shaft comprising a metal sleeve co-axial with the hosel; a plurality of laterally projecting fins lanced outward from the wall of the sleeve with an aperture in the wall at the base of each fin, said fins lying in longitudinal rows on the sleeve and extending in substantially radial direction, said fins being embedded in the plastic material of the head; and said plastic material extending into said apertures at least to the interior surface of the sleeve.

6. In a molded plastic head for a golf club having a shank and a hosel extending into the head through said shank; means in said hosel for securing said head to a shaft comprising a metal sleeve co-axial with the hosel for engaging the end of a shaft and tapering toward its lower end; a plurality of opposed laterally projecting fins lanced outward from the wall of the sleeve with an aperture in the wall at the base of each fin, said fins being spaced laterally and longitudinally on said sleeve, the surfaces of said fins forming an angle of at least 60° with the tangent to the sleeve at the base of each fin; said fins being embedded in the plastic material of the head, and said plastic material extending into said apertures at least to the interior surface of the sleeve.

7. In a molded plastic head for a golf club having a shank and a hosel extending into the head through said shank; means in said hosel for securing said head to a shaft comprising a metal sleeve co-axial with the hosel for engaging the end of a shaft and tapering toward its lower end; a plurality of laterally projecting D-shaped fins lanced outward from the wall of the sleeve with an aperture in the wall at the base of each fin, said fins projecting on alternate sides of said apertures and a plurality of apertures in the wall

of said sleeve opposite said lanced out fins, the latter apertures and said lanced out fins being distributed in spaced relation laterally and longitudinally of the sleeve; said fins being embedded in the plastic material of the head, and said plastic material extending into said apertures at least to the interior surface of the sleeve.

8. In a molded plastic head for a golf club, having a shank and a hosel extending into the head through said shank; means in said hosel for securing said head to a shaft comprising a metal sleeve tapering toward its lower end and co-axial with the hosel for engaging the end of a shaft extending part way into said sleeve; a plurality of laterally projecting fins lanced outward from the wall of the sleeve with an aperture at the base of each fin, the surfaces of said fins being parallel to a radial plane of the sleeve which intersects the center of the aperture at the base of the fin; said fins being embedded in the plastic material of the head, and said plastic material extending into the said apertures along the shaft-engaging portion of the sleeve to the interior surface thereof and extending through said apertures into the interior of the sleeve below said shaft-engaging portion.

9. In a molded plastic head for a golf club having a shank and a hosel extending into the head through said shank; means in said hosel for securing said head to a shaft comprising a metal sleeve tapering toward its lower end and co-axial with the hosel; means intermediate the end of the sleeve for securing same to a shaft extending part way into said sleeve; a plurality of laterally projecting fins lanced outward from the wall of the sleeve with an aperture in the wall at the base of each fin, the surfaces of said fins being parallel to a radial plane of the sleeve which intersects the center of the aperture at the base of the fin; a plurality of apertures in the wall of said sleeve opposite said lanced out fins, the latter apertures and said fins being distributed in spaced relation laterally and longitudinally of the sleeve, said fins being embedded in the plastic material of the head; and said plastic material extending into said apertures to the interior surface of the sleeve along the shaft-engaging portion thereof and extending into the interior of the sleeve below said shaft-engaging portion.

10. In a molded plastic head for a golf club having a shank and a hosel extending into the head through said shank; means in said hosel for securing said head to the shaft comprising a metal sleeve tapering toward its lower end and co-axial with the hosel; an internal threaded portion intermediate the ends of said sleeve for engaging threads on the end of the shaft inserted part way into said sleeve; a plurality of laterally projecting D-shaped fins lanced outward from the wall of the sleeve with an aperture in the wall at the base of each fin, said fins being alternately disposed on opposite sides of said apertures; a plurality of apertures in the wall of said sleeve opposite said lanced out fins, said latter apertures and the apertures at the base of said fins being distributed in spaced relation laterally and longitudinally of the sleeve; said fins being embedded in the plastic material in the head, and said plastic material extending into said apertures to the interior surface of the sleeve along the shaft-engaging portion thereof, and extending into the interior of the sleeve through said apertures below said shaft-engaging portion.

11. A metal sleeve for securing a molded plas-

tic article to a shaft comprising a plurality of laterally extending fins lanced outward from the wall of the sleeve with an aperture in the wall at the base of each fin, each of said fins lying in a longitudinal plane of the sleeve and extending in substantially radial direction therefrom.

12. A metal sleeve for securing a molded plastic article to a shaft comprising a plurality of laterally extending opposed fins lanced outward from the wall of the sleeve with an aperture in the wall at the base of each fin, said fins lying in longitudinal rows on the sleeve and extending in substantially radial direction therefrom; and a plurality of apertures in the wall of said sleeve opposite said lanced out fins, said apertures and said fins being distributed in spaced relation laterally and longitudinally of the sleeve.

13. A metal sleeve for securing a molded plastic head for a golf club to a shaft comprising means intermediate its ends for securing said sleeve to the end of a shaft; a plurality of laterally extending D-shaped fins lanced outward from the wall of the sleeve with an aperture in the wall at the base of each fin, said fins extending alternately from opposite sides of said aper-

tures and each of said fins being parallel to a radial plane intersecting the center of the aperture at the base of the fin; and a plurality of apertures in the wall of said sleeve opposite said lanced out fins, the latter apertures and said lanced out fins being distributed at spaced relation laterally and longitudinally of the sleeve.
